US0D1093136S

(12) **United States Design Patent** (10) **Patent No.:** **US D1,093,136 S**
Corbett et al. (45) **Date of Patent:** **** Sep. 16, 2025**

(54) **PEDESTAL SCREW INSERT**

(71) Applicants: **Christopher Corbett**, Valdosta, GA (US); **Roger Blaine Trivette**, Boiling Springs, SC (US)

(72) Inventors: **Christopher Corbett**, Valdosta, GA (US); **Roger Blaine Trivette**, Boiling Springs, SC (US)

(**) Term: **15 Years**

(21) Appl. No.: **29/947,798**

(22) Filed: **Jun. 18, 2024**

(51) **LOC (15) Cl.** **13-03**

(52) **U.S. Cl.**

USPC **D13/152**; D8/382

(58) **Field of Classification Search**

USPC D8/14, 349, 354, 382, 385; D13/110, D13/122, 133, 139.1, 139.3, 152, 154, D13/156, 184

CPC H02B 1/50; H02G 9/10

(57) **CLAIM**

The ornamental design for the pedestal screw insert as shown and described.

DESCRIPTION

FIG. 1 is an elevated perspective view of my design for a pedestal screw insert;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

1 Claim, 6 Drawing Sheets
